UNITED STATES PATENT OFFICE

GARNET W. MCKEE, OF ROCKFORD, ILLINOIS

FUEL BURNING DEVICE

Application filed May 14, 1927. Serial No. 191,326.

This invention relates in general to fuel mixing devices having mixing tubes which are inserted into furnace walls for the purpose of conducting combustible mixtures into the interiors of the furnaces.

Heretofore great difficulty has been encountered in providing burners which are able to operate satisfactorily with high temperature furnaces and which, when so located as to assure the maintenance of ignition, will not be destroyed by the heat of the furnaces. Various precautions have been resorted to, such as using nozzles or tubes composed of refractory material of a high grade or covered in part by such material. In other instances, the mixing tube or nozzle of the burner has been partially concealed in the furnace wall to protect it from reflected heat. But in most instances, whatever the construction was, all of these burners when used with high pressure gas or air in high temperature furnaces were either unable to keep the projected mixture burning as the flame was easily blown so far off the end of the nozzle that ignition of the mixture failed or the burner shortly burned itself out. My invention includes a mixing tube for use with a fuel mixer which is satisfactorily protected from high furnace temperatures and which also is constructed so as to decrease materially the likelihood of the flame being extinguished when the mixture is projected at high velocity.

One of the objects of this invention is to provide a mixing tube for conducting combustible mixtures into furnaces which is adapted to aid in the maintenance of combustion.

Another object of this invention is to provide a fuel burning device in which a mixing tube is so disposed in a furnace wall as to protect the tube from destruction by heat and yet promote and secure efficient and continuous combustion of the mixture projected from the tube.

Another object of this invention is to provide a fuel burning device in which a mixing tube is disposed in a furnace wall in such a manner as to protect it from radiated heat

and to cause the mixture projected from it to absorb heat from the walls of the tube.

Further objects, advantages and capabilities are inherently possessed by this invention and will later appear.

Referring now to the drawing, the figure discloses a mixer generally indicated as 11 into which is conducted high pressure gas through a pipe 12, the flow of gas being regulated by the valve 13. A movable shutter 14 regulates the admission of air in a manner well-known in this art. The high pressure gas is projected through the orifice 15 and entrains upon itself air which is drawn in past the shutter 14.

The mixer is secured to a fuel delivery tube 16 by means of the threads 17 and the inner end 18 of the tube extends into a passageway 19 in the furnace wall. In order that the tube may be rigidly secured in position, it is connected in a suitable manner to the plate 21, which plate is fastened to the wall of the furnace. The inner extremity of the mixing tube is chamfered as at 22. The passageway in the furnace wall then slightly expands as in the portion 23 and eventually terminates at the interior wall 24 of the combustion chamber. As will be obvious to one skilled in this art this fuel burning device is applicable to many types of furnaces and it will therefore be understood that the fragmentary portion of a combustion chamber wall 24 shown in the drawing may be a part of any one of many types of furnaces into which gaseous fuel mixtures are projected. An example of such a combustion chamber would be the ordinary rectangular chamber of a furnace for annealing small forgings.

When a mixture is being projected at high velocity through the mixing tube, it expands when passing through the expanding portion 18 of the tube and as it leaves the chamfered extremity 22, part of the mixture rolls off that edge in eddy currents which proceed to roll along the expanding portion 23 of the passageway in the fire brick wall 25. Consequently, the velocity in a longitudinal direction of the gas moving in these eddy currents will be considerably less than the velocity of

the gas moving through the central part of the passage. Though under abnormal conditions, the velocity of the flame which can progress back toward the tube may be less than the velocity of the central portion of the mixture, yet the rate of propagation of the flame will be greater than the general longitudinal motion of the eddy currents and will enable the flame to maintain itself in these eddy currents even though it might have a tendency to be blown off from the central portion of the projected stream of mixture. The flame thus maintained in the eddy currents will maintain the ignition of the entire mixture and will avoid the serious consequences which sometimes result from the blowing out of the flame without shutting off the mixer.

Not only does this apparatus provide a means for maintaining combustion under abnormal conditions, but it also protects the mixing tube from excessive temperature by disposing the extremity of the tube well back from the combustion chamber within the fire brick wall. With this device, it is not necessary to maintain an extremely high temperature near the end of the burner in order to obtain combustion because of the novel construction which resides in the chamfered edge of the tube. One is enabled to keep the extremity of the mixing tube well back from the combustion chamber to protect it from excessive heat.

By reason of the expanding taper of the tube near its extremity the mixture expands as it makes its exit from the tube and picks up heat from the tube walls, thus reducing the temperature of the tube and prolonging its life. This is a valuable feature since it is inevitable that some heat will be conducted through the fire brick directly to the tube.

By means of the disclosed construction, an apparatus is provided which is well adapted to maintain combustion under normal and abnormal conditions and which is so arranged as to promote the long life and efficient serviceability of the device.

It should be understood that the illustrated embodiment of the invention may be modified considerably without departing from the spirit and scope of the invention.

Having shown and described my invention,

I claim:

1. In combination with a combustion chamber wall having a passage therethrough, a fuel delivery tube extending into and terminating within said passage, means for projecting a combustible mixture through said tube, the extremity of the tube having a chamfered edge for producing eddy currents in the mixture along the wall of said passage, the internal diameter of the tube near its chamfered extremity being considerably less than the diameter of the part of the pas-

sage through which the mixture flows after leaving the tube.

2. In combination with a combustion chamber wall having a passage therethrough, a fuel delivery tube extending into and terminating in said passage, means for projecting a stream of combustible mixture through said tube and said passage, the posterior part of the tube having a taper expanding toward its extremity, said extremity having a chamfered edge for causing eddying currents of the mixture to roll more slowly along the posterior surface of the passage than the main body of the stream flows through the central portion of the passage.

3. In combination with a wall having a passage therein, a fuel delivery tube extending into and terminating within said passage, and means for projecting a combustible mixture through said tube, the extremity of the tube within the passage being chamfered toward the adjacent passage wall to cause part of the mixture issuing from the tube to roll off the end of the tube along the wall of the passage in eddy currents, the passage immediately beyond the end of said tube being free of obstructions such as might disrupt rearward propagation of flame through said eddy currents.

4. In combination with a combustion chamber wall having a passage therethrough, a tube projecting into and terminating in the passage for delivering a fuel mixture into the chamber and having a chamfered open end curved toward the passage wall constructed and arranged for causing part of the mixture delivered from the tube to roll along the surface of the passage in eddying currents having a general longitudinal motion slower than the velocity of the main stream and maintaining intimate contact with the main stream along the chamfered surface of said end, the passage being free from obstructions beyond the end of the tube.

In witness of the foregoing I affix my signature.

GARNET W. MCKEE.
